CAST WALL BRACKET

David K. Walz, Doraville, Ga., assignor to Lithonia Lighting, Inc., Conyers, Ga., a corporation of Georgia

Filed Oct. 1, 1965, Ser. No. 87,270

Term of patent 14 years

(Cl. D48—4)

FIG.1

FIG.4

FIG. 1 is a perspective view of a cast wall bracket, showing my new design;

FIG. 2 is a front elevation view thereof;

FIG. 3 is a top plan view thereof; and,

FIG. 4 is a side elevation view.

The broken line showing of a lamp globe is for illustrative purposes only.

I claim:

The ornamental design for a cast wall bracket, substantially as shown and described.
